[57] CLAIM

The ornamental design for a hoop toy, as shown and described.

DESCRIPTION

A hoop toy is disclosed that has utility as a play device in which a stick portion with an ornamental boot shape configuration has a pusher portion used to move a decorative hoop.

FIG. 1 is a front perspective view of the push stick, shown separately for clarity of illustration;

FIG. 2 is a rear elevation view thereof;

FIG. 3 is a side elevation view thereof, the opposite side being a mirror image;

FIG. 4 is a top plan view thereof;

FIG. 5 is a bottom plan view thereof;

FIG. 6 is a perspective view of a hoop, shown separately for clarity of illustration;

FIG. 7 is a side elevation view of FIG. 6, the opposite side being a mirror image;

FIG. 8 is a top plan view of FIG. 6, the bottom being a mirror image; and,

FIG. 9 is a perspective view of a hoop toy showing our new design.
